UNITED STATES PATENT OFFICE.

HUGH HILL, OF ANDERSON, INDIANA.

SUCTION SWEEPER.

Application filed January 5, 1922. Serial No. 527,217.

This invention relates to suction sweepers for both portable and stationary use.

It is the practice in some instances, particularly in office buildings and the like, to install a dust separator in some portion of the building, usually the basement, and then pipe the building and make connections in different rooms for the suction cleaning tools, and my invention applies to this class of devices, as well as to the small portable type, although the illustrations here show it only as applied to the latter.

The object of the invention is to make a device sufficiently simple, compact and efficient for use in this class of work, in which the dust laden air is drawn in and the dust separated therefrom by the action of centrifugal force.

The invention consists in mechanism attaining the foregoing objects, and in many features and details of construction which will be hereafter more fully set forth in the specification and claims.

Referring to the drawings, in which like numerals designate the same parts throughout the several views—

Figure 1 is a plan view, partially in section;

Figure 2 is a side view, largely in section, illustrating this invention in its preferred form;

Figure 3 is a side, and Figure 4 an end elevation of the exterior case mechanism most suited for use in this invention.

Externally, the device includes a generally circular case 10, contracted at its top in the curves 12 to the flat upper surface 14, to which is attached an electric motor retaining case 16, detachably secured in place by any suitable means such as the cap screws 18. Pivoted to the case 10 on opposite sides thereof, through the agency of suitable pivots 20, are the forked arms 22 of a conventional push handle 24, whose operating end, engaged by the operator to push the device over the carpet, does not enter into this invention and therefore is shown broken away. At the front of the case is a flaring, downwardly turned intake tube 26, terminating in the downwardly pointed intake nozzle 27 closely approaching the floor 28, as clearly shown in Figure 2. The case 10 is supported on small wheels 30 located at opposite ends of the intake nozzle and a bracket 32 resting on a suitably supported wheel mechanism 34 located at the rear edge

of the case. In the particular case here illustrated mechanism 34 comprises two parallel wheels journaled on a common pivot pin or shaft 36 extending through the bracket 32. This wheel arrangement gives the sweeper a three point support in traveling over the floor, which insures its being properly supported at all times with the nozzle 26 in close proximity to the floor.

As clearly shown in Figures 1 and 2, the lower half of the case 10 is truly cylindrical on all sides so as to form a central open bottom cavity 36, within which the dust retaining pan 38 may be inserted from the bottom. The upper edges of this dust pan 38 are adapted for detachable spring engagement with a downwardly turned flange 40 on an annular cover plate 42, which when the parts are in assembled position covers approximately the outer half of the pan. This cover plate 42 is rigidly secured by any suitable means, such as the screws 44, to the partition wall spokes 46, radiating from and, in the particular case here shown, integral with hub 48 of a wheel detachably secured by any suitable means such as the pin 50 from the shaft 52 of the motor contained within the case 16, which motor is of any conventional form and therefore not shown in the drawings, it being understood that electric current is supplied to the electric motor in any conventional manner well known in the electric art.

Also rigidly secured to the spokes 46, in the particular case here shown integral therewith, is a circular V-shaped guiding member 54, which happens in the particular case here illustrated, to be shown open at its top. This guiding member is made up of a vertical wall 56 located adjacent to the inner circumference of plate 42, and an angularly disposed wall 58 terminating in an upwardly turned flange 60 enclosing and freely rotating about the downwardly turned end portion 62 of the discharge port of the air intake pipe 26. The upper end of the vertical wall 56 is bent slightly inwardly in the curve 56^a and clears the internal edge of the annular ring 42 in the air discharge annular port 58, through which air may pass, as indicated by the arrows, from the interior of the dust pan to the annular air space 64 leading to the air discharge ports 66.

In the operation of a portable device, the operator pushes on the handle 24 to move the sweeper over the carpet or rug to be

cleaned, and at the same time by conventional electrical mechanism causes the motor in case 16 to continuously rotate the shaft 52. Rotation of the shaft 52 causes the spoked wheel 46—42—38—56 attached thereto to rapidly rotate to create a suction inside of the sweeper and draw dirt laden air through the nozzle 27 into the passage 26, from which it passes in the path shown by the arrows of Figure 2 down into the spaces 68 within the rotating wheel.

Thus, as the fan wheel rotates, a fluid stream passes through the cleaner and is given a whirling motion whereby, through centrifugal action, the heavier particles are projected outwardly. The guide 54 serves to reverse substantially the direction of flow of the fluid stream so that the heavier particles, which are moving outwardly under centrifugal action, may leave the main fluid stream and be deposited in the dust pan or container 38. Since the container 38 rotates at the same speed as the fan wheel, there are no eddy currents caused to stir up the precipitate or particles deposited.

When the sweeping operation is completed, or it is otherwise desired to clean the sweeper, the operator simply lifts the entire device from the floor sufficiently to get hold of the dust pan 38, whereupon he disconnects the upper edges of the pan from the flanges 40 in the obvious manner; empties the pan and returns it to place, whereupon the device is ready for repeated operation.

The design of the walls 56 and 58 is quite important in directing the flow of air in such manner that the dust is properly deposited and the cleaned air allowed to escape.

The walls 46 dividing the pan 38, when in operating position into radially disposed air chambers or sections, have to be generally radial; the ones shown are exactly radial so that the device will operate equally well when moved in opposite directions.

The tops 72 of walls 46 clear the lower ends of flanges 62 so that air flowing out of member 62 may easily divide itself between all the dust chambers as nearly equally as possible.

What I claim is:

1. In mechanism of the class described, a stationary casing, a dust pan within said casing, means for rotating said pan, means for drawing dust laden air into said pan at a point near its center, directing it through the pan towards the outer edge thereof, and delivering it from the pan at a point near its edge, whereby dust carried in said air is drawn by centrifugal force against the side of the pan and there retained.

2. In mechanism of the class described, a dust pan, means for rotating said pan, vertical, generally radial partitions dividing the pan into a plurality of air chambers, means for drawing dust laden air into said various

air chambers of the pan at a point near its center, directing it through the separate air chambers of the pan towards the outer edge thereof; delivering it from the pan at a point near its edge, whereby dust carried in said air is thrown by centrifugal force against the side of the pan and there retained in the various air chambers.

3. In mechanism of the class described, in combination with a case transportable over a floor, a dust pan, means for rotating said pan, generally radial partitions dividing the pan into a plurality of chambers, means for drawing dust laden air from the floor into said various chambers of the pan, directing it through the separate air chambers of the pan, delivering it from the pan, and thence out of the case, whereby dust carried in said air is thrown by centrifugal force against the side of the pan and retained in the various chambers.

4. In mechanism of the class described, in combination with a case transportable over a floor, a dust pan, a motor mechanism carried by the case for rotating said pan, generally radial partitions dividing the pan into a plurality of chambers, means for drawing dust laden air from the floor into said various chambers of the pan at a point near its center, directing it through the separate chambers of the pan, and delivering it from the pan so as to cause the air current to loop back on its path, whereby dust carried in said air is deposited in the pan.

5. In a cleaner, the combination comprising a casing provided with a nozzle to serve as an air inlet and with a spaced opening to serve as an air outlet, a motor on the casing provided with a shaft extending through the casing, a pan supported on the motor shaft beneath and within the casing to be rotated thereby, and means for drawing a current of air in through the nozzle and spreading it by whirling motion into a confined rotating annulus within the pan to project the heavier particles out of the air stream, and means for guiding the cleansed air out through the outlet of the casing.

6. In mechanism of the class described, a dust pan, means for rotating said pan, generally radial partitions dividing the pan into a plurality of air chambers, means for drawing dust laden air into said various air chambers of the pan at a point near its center, directing it through the separate air chambers of the pan towards the outer edge thereof; delivering it from the pan at a point near its edge, whereby dust carried in said air is thrown by centrifugal force against the side of the pan and there retained in the various air chambers, and means removably mounting the dust pan with reference to the other parts of the device.

7. In mechanism of the class described, a

rotatable dust pan, an annular, circular V-sectioned guiding member inserted in the pan providing an annular vertical wall adjacent to but separated from the outer wall of the pan, and an angularly inclined annular wall leading from the bottom of said vertical wall upwardly towards the center of the pan so as to leave an air intake space at the central top portion of the pan, and means for forcibly carrying air into the pan through said central opening down around the said guiding means, then outward outside said vertical wall, whereby dust contained in the air so carried through the pan is separated from the air and thrown against the side walls of the pan for the purposes set forth.

8. In mechanism of the class described, a casing, a rotatable dust pan therein, an annular guiding member inserted in the pan providing an annular vertical wall adjacent to but separated from the outer wall of the pan, and an angularly inclined annular wall leading from the bottom of said vertical wall upwardly towards the center of the pan so as to leave an air intake space at the central portion of the pan, an annular cover over the outer portion of the pan but separated from the vertical wall of the V member so as to form an air discharge port from the pan, said V member being so formed that the discharge port is radially nearer the center of the pan than the lower part of the vertical wall of the V member, and means for forcibly carrying air into the pan through said central opening down around the said guiding means, then outward outside said vertical wall, whereby dust contained in the air so carried through the pan is separated from the air and thrown against the side walls of the pan for the purposes set forth.

9. In mechanism of the class described, a casing, a rotatable fan wheel for drawing a fluid stream into the casing and giving it a whirling motion, a container disposed to rotate with the fan wheel to receive the precipitate separated from the fluid by centrifugal action, and a guide carried by the fan wheel disposed to cause substantially a reversal of the direction of flow of the fluid stream, thereby to project the heavier particles out of the fluid stream and deposit them into the container.

In witness whereof, I have hereunto subscribed my name.

HUGH HILL.
